CARBON PILE REGULATOR

Arthur James Stephen Brown, Bromley, and
Aubrey Laurence Ash, Thorpe Bay, England,
assignors to J. Stone & Company Limited,
Deptford, England, a corporation of Great
Britain

Application October 4, 1934, Serial No. 746,898
In Great Britain July 28, 1933

7 Claims. (Cl. 171—229)

This invention concerns improvements in and relating to carbon pile regulators, more particularly for use in electrical train lighting and heating installations, battery charging installations and the like.

- For certain purposes in such installations, it is desirable to control one factor in two different ways, or in dependence upon two different factors, at different stages of the regulation process. In particular, for battery charging purposes, it may be desired to charge the battery initially under current control, e. g. at constant current, and subsequently under voltage control, e. g. at constant voltage. With such a charging process, complete reconditioning of the battery can be effected in the minimum period feasible without overloading the generator, and the danger of detrimental effects due to over-charging, sulphation and so forth can be largely avoided.
- 20 The principal object of the present invention is to provide a simple and reliable carbon pile regulator which permits of the exercise of such a double control, especially for the purposes just mentioned.
- 25 One embodiment of the invention by way of example will now be more fully described with reference to the accompanying drawing, in which:—

Figure 1 is a front elevation of the regulator partly in section,

Figure 2 is a vertical section thereof, and
Figure 3 a circuit diagram.

The regulator illustrated comprises two electromagnetic units mounted back to back with their back-plates integral with a common frame 101. A carbon pile resistance is mounted between said units upon a plate 102 secured to the frame 101, said resistance thus forming a separately removable and replaceable unit. The magnet and spring systems of the units may advantageously be of either of the types described in the specifications of United States patent application of Alfred H. Chilton, Serial No. 683,557, filed August 3, 1933, and United States patent 40 to Alfred H. Chilton, No. 1,963,825, dated June 19, 1934. In the example illustrated, the magnet and spring systems are of the type described in Patent No. 1,963,825. Essentially the magnet systems comprise magnets 21, 22 carrying windings 31, 32, and spindles 61, 62 upon which rotors 71, 72 are mounted to rock between the poles of said magnets. The spring systems, which are matched with their respective magnet systems, comprise tension springs 321, 322 connected by flexible tapes 33 to segmental discs 161, 162 fast

on the spindles 61, 62, adjustment means 35 and 36 being provided for setting the initial spring tension and rate respectively. Movement of the discs 161, 162 is damped by similarly disposed dash-pots one of which is shown at 37 and limited by co-acting stop-means 39, 40. The pile unit comprises a crank 17 pivotally connected at 18 to a push rod 19 which acts through a compression plate 20 upon the carbon pile 21. At its upper end the pile bears against an abutment plate 22 having an upward extension 23 which is pivotally connected at 24 to an anchorage 25. This anchorage is mounted in a forward extension 103 of the plate 102 and can be vertically adjusted and locked by a knurled nut 15 21 and lock nut 28 engaging a threaded stem on said anchorage. The arrangement of the pile itself is thus essentially similar to the arrangement adopted in the above mentioned specifications.

For the purposes of the present invention, however, the crank 17, with which is connected a lever 13, is mounted upon a ball-bearing on a separate spindle 14 located between the aligned spindles 61, 62 of the magnet systems and separately supported in forward extensions 104 from the plate 102. Connected to the lever 13 is a tension spring 75 which is adjustably anchored at 105 and serves to maintain the pile 21 under an initial compression which is kept practically constant despite wear in the pile. Mounted peripherally upon the discs 161 and 162 of the units are fingers 761, 762 extending horizontally to points underneath the end of the lever 13 which has spaced abutment surfaces 77 each engageable by an adjustable abutment 78 on one of said fingers. The regulator is set so that in the initial or inoperative condition the abutments 78 are both just out of contact with the surfaces 77.

For the above mentioned case of battery-charging under dual control, the winding 31 of one unit is excited by or proportionately to the dynamo output current and the other 32 by the charging voltage (Figure 3) through a temperature compensating resistance 106. The pile 21 is disposed in series with the field 107 of the dynamo 108 from which the battery 109 is charged. Upon commencing to charge a discharged battery, the latter tends to take a relatively large current at a low voltage. The effect of the large current in the winding 31, causes the rotor 71 to be attracted and to bring the finger 761 into contact with the lever 13, thereby rocking the latter in the direction for decom-

pressing the pile 21. The resultant increase of the pile resistance reduces the excitation and thus the current output of the dynamo. By suitable design of the magnet system 3¹, 7¹, the 5 charging current can by this means be kept substantially constant. Meanwhile the charging voltage on the winding 3² is too low to cause attraction of the rotor 7² so that, in this initial stage, the charging is solely under current control.

As charging proceeds, however, the charging voltage eventually reaches a value at which the rotor 7² is attracted, causing the finger 16² to overtake the lever 13 and momentarily to assist 15 the finger 16¹ in decompressing the pile 21. The resultant additional increase of resistance of said pile at once acts to reduce the charging current, so that the said other finger 16¹ tends to drop away from the lever 13. As charging proceeds, 20 this effect is accentuated and the subsequent charging is completed solely under voltage control. The point at which the control is changed may be set to suit requirements but will generally be set for a comparatively advanced stage in the 25 charging process.

If it is desired to increase the charging current to the battery during the initial part of the period of charging under substantially current control (when the charging voltage is lowest), 30 the current-controlled unit may carry, in addition to the winding 3¹, a small proportion of turns excited proportionally to the battery voltage.

We claim:

35 1. Electro-magnetic regulator adapted for regulating in different ways at different stages of the regulation, comprising a single carbon-pile resistance, two magnet systems having independent excitation windings and independent rotors, spring systems respectively connected with the said rotors and matched with and opposing the said magnet systems, and independent pressure-controlling means for the said resistance each operatively connected with one of the said 40 rotors and each engageable, one at a time, with said carbon-pile resistance for the sole control of the said resistance over one stage of the regulation.

50 2. Electro-magnetic regulator adapted for regulating under current and voltage control respectively at different stages of the regulation, comprising a single carbon pile, two magnet systems having independent excitation windings for current and voltage excitation respectively 55 and having independent rotors, spring systems respectively connected with said rotors and matched with and opposing the said magnet systems, and independent pressure controlling means for the carbon pile each operatively connected with one of the said rotors and each engageable, one at a time, with said carbon-pile

resistance for the sole control of the said carbon pile over its respective stage of the regulation.

3. Electro-magnetic regulator, comprising two independent magnet systems having rotatable rotors each having a spindle, said spindles being 5 in alignment with each other, a single carbon-pile disposed between the said magnet systems, spring systems operatively connected to the said rotor spindles, and independent pile-controlling members operatively connected to respective rotor-spindles and adapted for acting upon the pile independently of each other.

4. Electro-magnetic regulator, comprising two independent magnet systems having rockable rotors, a common carbon pile, a common pile-controlling lever mounted independently of the said 15 rotors, and pile controlling fingers operatively connected to respective rotors and each independently engageable with the said lever for excising sole control of the said pile.

20 5. Electro-magnetic regulator, comprising two independent magnet-systems having rockable rotors, spring systems acting upon the said rotors, a carbon pile, pile-controlling means operatively connected to respective rotors and en- 25 gageable, one at a time, with the said pile for the sole control thereof over a range of operations, and separate spring means acting upon the said pile for maintaining it under initial compression.

6. In a regulator device, a resistance element 30 variable under compression, a pivoted member, a compression member acting at an end of said element, and a link interconnecting an end of said pivoted member and said compression member, a pair of electro-magnets, a pair of independently rotatable shafts, an armature for each magnet secured to each of said shafts, lateral extensions secured to said pivoted member adjacent its end opposite said link, an arm on one of said shafts and a second arm on the other of 40 said shafts, said arms being movable to engage said lateral extensions as said shafts rotate, a spring acting on one of said armatures, a second spring acting on the other of said armatures, said springs tending to rotate said shafts in a 45 direction to move said arms out of engagement with said lateral extensions, said shafts being rotatable independently to bring either of said arms into engagement with its respective lateral extension upon energization of either of said 50 magnets to decompress said pile to a degree dependent upon the degree of energization of one of said magnets alone.

7. The invention as defined in claim 6 wherein 55 said springs are matched with their respective magnets so that said armatures move in response to critical values of excitation of their respective magnets.
